United States Patent Office.

JOHN FRENCH, OF NEWPORT, KENTUCKY.

Letters Patent No. 67,866, dated August 20, 1867.

IMPROVEMENT IN BOILER GAUGE-COCKS.

The Schedule referred to in these Letters Patent and making part of the same.

TO ALL WHOM IT MAY CONCERN:

Be it known that I, JOHN FRENCH, of Newport, Campbell county, State of Kentucky, have invented a new and useful Improvement in the Manner of Constructing Gauge or Try-Cocks for steam-boilers; and I do hereby declare that the following is a full, clear, and exact description of the same, reference being made to the annexed drawings and making a part of this specification.

The nature of my invention consists in providing and using in gauge or try-cocks for steam-boilers a spiral or twisted valve-stem, so constructed that when being operated the steam or water escaping will cause the spiral valve-stem to revolve, and thus keep the body of the cock free and clear from any deposit of mud, lime, or substance, and by this means always insure the proper working of the cock. In the annexed drawings—

Figure 1 is a section showing the cock with the spiral valve-stem attached and in place; also the button or cap upon the outer end of the stem.

Figure 2 represents a view of the spiral valve-stem.

Figure 3, the body of the cock, and

Figure 4 the cap or button.

The body of the cock, fig. 3, is made of cast brass or other metal, of suitable form and size, through the centre of which is drilled or cast a hole, of equal diameter, to receive the spiral valve-stem, and has at each end a bevel valve-seat. The spiral valve-stem, fig. 2, is made of iron, steel, or other metal. I make them of iron, forged the proper length, and about five-eighths of an inch wide, and three-sixteenths of an inch thick, then reduce the outer end to a round about one inch in length, and three-sixteenths of an inch in diameter. The object of making the stem round at the outer end is to secure the cap or button, through which the stem revolves. On the other end of the stem is forged a simple conical valve, and turned to fit the valve-seat on the inner end of the body. The spiral form of the stem is had by heating and twisting in the usual way. The cap or button, fig. 4, is of brass or other metal, and has a hole drilled through the centre to secure the round end of the stem which passes through, and is held in place by a rivet or nut on the end of the stem, but left loose so as to allow the stem to revolve in the cap. The under side of the cap is turned conical so as to fit the bevel valve-seat on the outer end of the body, fig. 3, so that the cock being used, the button or cap is pressed down upon the outer end of the body, the cone will fit into the valve-seat on the body and form a tight joint, and prevent the steam from being forced out upon the operator.

What I claim as my invention, and desire to secure by Letters Patent, is—

1. The spiral valve-stem A, in combination with the body of the cock C.
2. The spiral valve-stem A, the button or cap B, in combination with the body of the cock C, substantially as described.

JOHN FRENCH.
